(57) **CLAIM**

The ornamental design for a torch nozzle for lighter, as shown and described.

DESCRIPTION

FIG. 1 is a perspective view of my new design.

FIG. 2 is a front view thereof.

FIG. 3 is a rear view thereof.

FIG. 4 is a left end view thereof.

FIG. 5 is a right end view thereof.

FIG. 6 is a top view thereof.

FIG. 7 is a bottom view thereof; and,

FIG. 8 is another perspective view of my new design, wherein the action figure is illustrated in an open condition. The broken line environmental showing is for illustrative purposes only and forms no part of the claimed design.
